(21) Appl. No.: **29/220,310**

(57) **CLAIM**

(22) Filed: **Dec. 29, 2004**

The ornamental design for a pneumatic power device with electric cable supported on pressure air conduit, as shown and described.

(30) **Foreign Application Priority Data**

Jul. 1, 2004 (SE) 04-0488

DESCRIPTION

(51) **LOC (8) Cl.** **08-05**

FIG. 1 is a rear, top, right-side perspective view of a pneumatic power device with electric cable supported on pressure air conduit showing my new design;

(52) **U.S. Cl.** **D8/68**

FIG. 2 is a front, bottom, left-side perspective view thereof;

(58) **Field of Classification Search** D8/14.1,

FIG. 3 is a front elevational view thereof;

D8/61, 62, 63, 64, 65, 66, 67, 68, 69, 70;
81/57.11, 429, 464, 465, 466, 469, 489; 173/13,
173/104, 114, 168, 169, 170, 171, 178, 201,
173/211, 213, 217; 408/20, 124, 125, 234,
408/241 R; 451/358; 310/50; 227/8, 113,
227/114, 120, 130, 136, 142

FIG. 4 is a rear elevational view thereof;

See application file for complete search history.

FIG. 5 is a left-side elevational view thereof;

FIG. 6 is a right-side elevational view thereof;

FIG. 7 is a top plan view thereof; and,

FIG. 8 is a bottom plan view thereof.

(56) **References Cited**

The electric cable and pressure air conduit are shown broken away in all of the figure views in order to indicate that a specific length of electric cable and pressure air conduit form no part of the claimed design.

U.S. PATENT DOCUMENTS

The broken line showings in the drawings are for illustrative purposes only and form no part of the claimed design.
